UNITED STATES PATENT OFFICE.

BIRNEY DYSART, OF ST. LOUIS, MISSOURI, ASSIGNOR TO DALTON ADDING MACHINE COMPANY, OF ST. LOUIS, MISSOURI, A CORPORATION OF MISSOURI.

ADDING AND RECORDING MACHINE.

1,098,714.

Specification of Letters Patent. Patented June 2, 1914.

Application filed July 12, 1909. Serial No. 507,274.

To all whom it may concern:

Be it known that I, BIRNEY DYSART, a citizen of the United States, residing at St. Louis, Missouri, have invented a new and useful Adding and Recording Machine, of which the following is a specification.

This invention relates to adding and recording machines, and one object of this invention is to produce an adding machine having an adding mechanism operable to perform adding functions, such as carrying throughout, and provided with mechanism whereby carrying may be interrupted at any predetermined point in the adding mechanism.

Another object is to provide a machine comprising numeral keys, a mechanism operable to add numbers struck on the keys, in combination with mechanism for operating said adding mechanism effectively to determine and represent a number which is the remainder or difference between the number or total represented in said adding mechanism and another number subsequently struck on the keys, said adding mechanism having only one direction of operation to perform both adding and subtracting functions.

Another object is to provide mechanism in an adding machine whereby, after the minuend has been introduced into the adding mechanism, transferring or carrying may be interrupted in the next higher order from the minuend so as to enable subtraction to be performed by the use of the complementary number of the subtrahend extending only to the order to which the minuend extends, irrespective of the value of such order.

In a companion application I have shown and described mechanism for use in mathematical calculations involving subtraction in which the entire adding mechanism is brought into use at each operation for subtraction, all that part of the adding mechanism in higher orders from the minuend being operated to receive complementary 9's of the subtrahend, so that when the subtrahend complement is introduced into the adding mechanism carrying or transferring will be performed throughout the adding mechanism, clearing that portion of the adding mechanism above the highest order of the remainder.

The present invention differs from that

disclosed in the said companion application in dispensing with the use of the complementary 9's beyond the highest order of the minuend, and another object of the invention is to produce mechanism whereby carrying or transferring may be interrupted at the proper point in the adding mechanism to enable the operator to perform calculations in this way.

As in the said companion application, the key board of the machine in which my present invention is embodied, includes a set of keys having two sets of figures thereon, one set of which indicates the positive value of the key and the mechanism to be operated thereby, and the other the complementary value of the key, which enables the operator readily to select the proper keys for setting up the subtrahend complement in all cases of subtraction.

In addition to the foregoing specified objects and advantages, others will appear from the following description in which reference is made to the accompanying drawings, in which—

Figure 1 is a side elevation of an adding and recording machine of a well known type, with part of the case broken away or removed to disclose parts of the present subject matter. Fig. 2 is a diagrammatic plan or chart illustrating the arrangement of the keyboard in which the figures uppermost on the several keys indicate the positive values of the keys, and the figures below indicate the subtrahend or negative values. Fig. 3 illustrates a specimen or example of subtraction in which the minuend and subtrahend and remainder are recorded. Fig. 4 illustrates a complete example of subtraction in which the subtrahend, the minuend, the minuend complement and the remainder are recorded. Fig. 5 is a vertical sectional view of the rear portion of the machine showing parts of the present invention. Fig. 6 is a vertical sectional view of the rear portion of the machine at the right hand side. Fig. 7 is a rear elevation showing the relation of the subject matter of the present invention with respect to the other operating parts. Fig. 8 is a perspective view of the devices employed to interrupt carrying or transferring in the adding mechanism. Fig. 9 is a perspective view of one of the stop devices whereby the carrying is interrupted. Fig. 10 is an enlarged view showing the normal

position of the devices for interrupting carrying. Fig. 11 illustrates said devices adjusted to prevent carrying. Fig. 12 is a view similar to Fig. 11 showing the return devices in engagement with the stops by which carrying is interrupted.

The greater portion of the mechanism contained in the adding machine with which I have illustrated my present invention is disclosed in the application of Hubert Hopkins, Serial No. 140,390, filed January 24, 1903, and the corresponding British Patent No. 854, of 1904, and these machines are also well known commercially at the present time. The said machines include a keyboard comprising a set of ten keys 1 having levers extending rearwardly and provided at their rear ends with vertical extensions or hammers 2. On rails 3 (Figs. 5, 6 and 7) extending transversely above the rear ends of the key levers a carriage 4 is mounted, having suitable anti-friction devices 5 operating on the rails. The carriage is provided with a rack 6 projecting leftwardly with respect to the operator and in mesh with a gear segment 7 rigidly attached to the upper end of a vertical shaft 8. An escapement bar 9 rests upon the key levers and is provided with an escapement device 10 engaging with a tooth segment 11 attached to the shaft 8. A spring 12 actuates the carriage leftwardly and it is stepped along from right to left when the keys are operated, movement being permitted by operation of the escapement 10. Within the carriage a series of rows of pins 13 are movably carried, and in idle position the row of pins at the left are supported immediately above the extension 2 whereby operation of a key will move or set up a corresponding pin in the carriage, and through operation of the escapement 10 will permit the carriage to be moved one step leftwardly which is sufficient to bring the next row of pins over the ends of the key levers. This operation is repeated whenever any key is pressed and is well known in adding machines of the cross carriage type. These machines also include a series of racks 14 suspended by vertical extensions from the shaft 15 and connected with type carriers 16 by pin-and-slot connections 17. The type carriers also swing from the shaft 15 and through the pin and slot connections have a certain independent movement without corresponding movement on the part of the racks. Each type carrier is provided with a rearward extension 18, and said extensions are connected with their respective racks by means of springs 19 thereby connecting the racks rearwardly with respect to the type carriers.

Arms 20 swing from the shaft 15 and have a bar or cross piece 21 supported in front of the vertical portion of the racks

and type carriers, and holding them normally in idle position. Extensions of the arms 20 support a rod 22 which is connected with the extensions 18 of the type carriers by means of springs 23, from which it follows that when the arms 20 are swung forwardly the springs 23 will tend to actuate the type carriers forwardly. The springs 19 will tend to detain the racks until the type carriers reach the limit of their independent movement permitted by the pin-and-slot connections 17, for which the racks also will be moved.

When any number has been set up in the carriage by operation of the keys as above described, the arms 20 and the cross piece 21 supported thereby are swung forwardly and the type carriers and racks also move until further movement thereof is stopped by engagement of heels 24 on the racks with the pins 13 which have been set up in the carriage. This movement is arranged to be sufficient to aline the type 25 on the type carriers in proper recording position adjacent to the platen 26 whereon records may be made by driving the type to print through operation of the spring-impelled hammers 27.

Adding mechanism 28 comprising a set of wheels mounted upon a shaft 29 are arranged to engage with the racks on their return movement and thereby receive and add the number which had been set up in the carriage and recorded.

The carriage supports a plate 30 whose rear edge is normally in front of the heels 24. As the carriage is stepped across the machine, the plate 30 moves successively from in front of the heels 24 releasing one rack at each step, so that as many racks will be free to move as there were digits in the number struck on the keys. Upon operation of the racks and type carriers to record and add the number which has been represented in the carriage, all those racks and type carriers which are not necessary will be detained from operation by the plate 30.

Carrying from lower to higher orders in the adding wheels is effected by moving the racks 14 rearwardly a short distance beyond their idle position whenever carrying is necessary, such result being accomplished through any well known tripping devices which may be used in connection with the adding wheel. In these machines the carrying or transferring mechanism is continuous from the lowest to the highest order, so that carrying may be accomplished throughout the adding mechanism or at any point therein whenever it is necessary to produce the correct result or total. The carrying is effected in these machines in substantially the same manner as in the machine of the British patent, by causing the racks 14 to be moved rearwardly the required distance by

their springs 19. The trips actuated by the adding wheels, whereby this carrying or transferring is permitted, are not shown, and are not affected by the present invention, but only the racks themselves are affected, being held and prevented from carrying at the desired point. These devices for holding of the racks and preventing them from carrying or transferring I have termed "means for interrupting the carrying or transferring." I employ this term in its broadest sense, and mean and include thereby any devices or elements which will coöperate with the adding wheels or their actuating racks effectively to stop, prevent or interrupt carrying beyond any selected order above or beyond which carrying or transferring would be effected except for manipulation of said means.

Adding machines of this type as well as others, are frequently employed to perform examples, so called, of subtraction. These examples really are examples of addition in which the subtrahend is introduced into the machine by its complement up to the full capacity of the adding mechanism. By complement, used in this sense, is meant that number which added to the subtrahend will add beyond the capacity of the machine and restore all of the adding wheels to idle position.

Referring to Figs. 3 and 4 for further illustration, the number "A" represents the minuend which has been recorded and introduced into the adding mechanism; the number "B" represents the subtrahend which has been recorded but not added and is to be subtracted from the minuend. In the machines of the cross carriage type at present on the market, so far as I am informed, and in many or all other adding and listing machines, subtraction would be performed by introducing into the adding mechanism the full complement of the number "B" and adding said complementary number to the minuend "A," which would be effective to produce and retain within the adding mechanism the remainder or difference between the minuend and the subtrahend. Assuming that there were six orders in the adding mechanism, the complement of the number "B" as shown requires that 9 be introduced into the adding mechanism in the highest order, the complement of the subtrahend being at the same time introduced into the lower orders will cause the adding mechanism to be operated to position and represent the difference between the minuend and the subtrahend. Should the adding mechanism extend beyond the sixth order to which the minuend extends, it is necessary in the machines at present in use to introduce 9's to the left of the subtrahend complement up to the highest order of the adding mechanism, which operation is

tedious and requires care on the part of the operator to avoid mistakes. The complementary 9's are necessary in order that when carrying is effected beyond the highest order of the minuend all the adding wheels in higher orders will be returned to idle position in order that the wheels of the lower orders may properly represent the remainder or difference.

My present invention overcomes the necessity for introducing the full complement of 9's by interrupting carrying beyond the highest order of the minuend, and requires only that the operator shall introduce 9's in higher orders from the subtrahend only to the highest order of the minuend. This is illustrated in Fig. 4 in which the minuend extends to the 6th order and the subtrahend "B" to the fifth order, in which instance it is necessary only for the operator to introduce into the machine one 9 followed by the five complementary orders for the subtrahend.

In carrying out this invention, I provide a key 31 extending through a slot in the front of the case, and having its lever resting upon a projection 32 on the bell crank lever 33. A link 34 connects the opposite arm of the bell crank lever 33 with an arm 35 attached to the rock-shaft 36 at the rear of the machine. (Fig. 5.) The rock shaft 36 is encircled by an eccentric sleeve 37 which in turn is encircled by a sleeve 38. At one end of the sleeve 38 is a forwardly projecting arm 39 having a roller 40, said arm 39 being provided also with a downward extension 41. The opposite end of the sleeve 38 has an arm 42 attached thereto corresponding to the arm 41 and between the lower ends of said arms bar 43 is attached. To said bar 43 a plate 44 is secured, said plate being provided with a series of depending arms having rearward extensions 45 at their lower ends. A shaft 46 rearward from the arms of the plate 44 supports a series of stop members 47 which project forwardly between the arms of the plate 44, each of said stops having a shoulder 48 above the shaft 46 and a lateral shoulder 49 below said shaft.

The stop members 47 (Figs. 6, 10 and 11) have two notches 50 in their rear ends, which are engaged by detent springs 51 whereby said stops will be held in their two adjustments, but may be forcibly moved from one adjustment to the other as required in operating the machine. The bar 43 has its lower edge extended rearwardly as shown in Fig. 6. A spring 52 actuates and holds the link 34 in its rearward position, also holding the shaft 36 in position so that the eccentric sleeve 37 on said shaft occupies substantially the position shown in Fig. 6 in which the arms 41 and 42 are in their lower adjustment. Depression of the

key 31 rocks the shaft 36 and thereby raises the arms 41 and 42 bringing the extended portion of the bar 43 above the projections or shoulders 48. The heel plates 24 are provided with notches 53 which during operation for regular addition receive the forward ends of the stops 47 when the racks move rearwardly for carrying. In order to interrupt carrying or transferring, it is only necessary to prevent the racks 14 from moving rearwardly beyond their idle position, and this may be accomplished by moving the stops 47 so that the heels 24 will engage against the forward ends thereof. The link 54 (Fig. 6) found in the machine extends obliquely downwardly and forwardly, and is reciprocated at each operation of the type carriers and racks. I modify this link by forming a surface 55 which operates against the roller 40 without moving the arm 39 until near the forward stroke of the link, at which time a cam 56 on the link quickly oscillates the arm 39 and thereby the two arms 41 and 42. During ordinary addition this operation on the part of the arms 41 and 42 produces no effect upon the stops 47. However, should the key 31 be depressed and the arms 41 and 42 raised as previously described, the ends of the arms 45 will be immediately in front of the shoulders 49 on the stops 47. When so adjusted and the type carriers and racks and the link 54 are moved forwardly, the arms 45 will be forced against the shoulders 49 with sufficient force to swing the stops 47 to their lower position as shown in Fig. 12, the detent latch springs 51 permitting and holding the stops in such adjustment. When so positioned the stops are below the notches 53 and will act as abutments for the heels on the racks and thereby prevent backward movement of the racks which is necessary to effect carrying.

The carriage 4 has a plate 57 (Figs. 6 and 7) attached to its rear side and extending above the carriage so that when said carriage is moved leftwardly in setting up numbers therein, said plate is moved successively under the stops 47. Said plate extends to a sufficient height to constitute a stop or abutment for those stops 47 under which it becomes positioned, thereby preventing such stops from being lowered. This arrangement is intended to permit carrying or transferring from lower to higher orders in that part of the adding mechanism which is to be operated.

When the link 54 is moved forwardly with the type carriers and racks, the cam 56 on said link will swing the arms 41 and 42 rearwardly. Operation of the subtraction key 31 and its connected parts raises said arms 41 and 42 sufficient to bring the spring-arms 45 in front of the shoulders 49 on the stops 47. Rearward operation of the

arms 41 and 42 causes the arms 45 to engage the shoulders 49 and thereby to lower such of the stops 47 as are at the left of the abutment plate 57, while those stops under which said abutment plate extends will be supported in position to register with the notches 53 in the heels 24 of the racks. In Fig. 10 is illustrated the relative positions of the stops and the abutment plate showing the stops supported by said plate to register with the notches in the heels of the racks, while in Fig. 12 the stops are shown depressed to constitute abutments for heels on the racks to prevent backward movement and thereby prevent carrying in the adding mechanism. In this way carrying will be interrupted beyond the number introduced into the adding mechanism whenever the subtraction key is depressed. When the subtraction key is released, the spring 52 restores said key and the parts operated thereby to idle position, rocking the eccentric 37 effectively to move the arms 41 and 42 to their lower positions, bringing the rearward extension of the plate 43 in front of the shoulders 49 which are above the shaft 46. The next operation of the link 54 which is necessary to restore the racks to their idle positions will swing the arms 41 and 42 rearwardly and cause the plate 43 to engage the shoulders 49 as shown in Fig. 12, and restore the stops 47 to their idle position. The detent latches 51 permit this forcible movement of the stops and hold them in their different adjustments except when moved as described.

From the foregoing it will be understood that the position of the carriage 4 determines to what order carrying or transferring is performed in subtracting operations. The plate 57 supports and prevents depression of the stops 47 in all numerical orders occupied by the carriage. Thus, if the carriage has been moved to the sixth order, the stops 47 in the six orders occupied by the carriage 11 will be upheld by the plate 57 so that the racks 14 in the same six orders may operate in carrying or transferring operations. Operation of said racks in carrying or transferring operations takes place because the 11 stops 47 which are supported by the plate 57 will be received in the notches 53, thereby permitting the racks in said six orders to move rearwardly in carrying or transferring throughout said six orders. This is true in 12 whatever position the carriage may be, so that the position of the carriage determines which stops 47 shall be retained in position to permit transferring or carrying operations by the racks 14. The stops 47 which 12 are not supported by the plate 57 are controlled by the subtracting key 31 and its connections to prevent carrying or transferring beyond the order to which the carriage has been moved.

The stop 47 in units order is adjusted so that its normal or idle position is above the notch 53 on the units rack. This adjustment is provided for the reason that ordinarily carrying or transferring into units order does not occur, and therefore the units rack never moves rearwardly beyond its normal or idle position in performing examples of ordinary addition or multiplication. When the arms 41 and 42 are raised and are swung rearwardly as above described, the arm 45 for units stop will engage the shoulder 49 on said stop and move said stop into alignment with the notch 53 in the heel of units rack. When the racks move rearwardly after this operation, units rack travels one step or space beyond its idle or normal position which is effective to introduce or add "1" in the units adding wheel in addition to the unit which had been set up in the carriage or which was previously represented in said units adding wheel.

In operating this machine to perform examples of subtraction, the minuend number or the series of numbers whose total constitutes the minuend are introduced into the adding mechanism through operation of the carriage 4 and the racks 14 in the usual way. Then the complement of the subtrahend number including 9's up to the highest order of the minuend is set up in the carriage, then the subtraction key 31 will be depressed to adjust the stops 47 to prevent carrying beyond the highest order in the adding mechanism, and said complementary number introduced or added into the adding mechanism. This operation causes the adding mechanism to produce or determine the difference or remainder between the subtrahend and the minuend.

To facilitate the selection of the complementary numbers, I arrange the keys each with two characters thereon as shown in Fig. 2, the upper or larger characters indicating the positive values of the respective keys, while the lower characters indicate the digits of which the upper digits are the complements. The minuend number therefore will be introduced into the machine by striking the keys indicating such number by the digits uppermost on the keys, while the subtrahend complement will be introduced into the machine by operation of the keys indicating the subtrahend by small or lower characters. It will be remembered, however, that the operator must set up as many digits in the subtrahend as there are in the minuend, and in all cases must set up the digit "9" in each order beyond the highest order of the subtrahend up to the highest order of the minuend. A specimen of this work is shown in Fig. 4, in which the subtrahend "B" is to be subtracted from the minuend "A." The fact that the minuend extends to the sixth order while the subtrahend

extends only to the fifth order, requires that the operator in setting up the subtrahend complement shall set up one order in addition which shall contain the digit "9." The subtrahend complement as shown at 70 "C" is readily determined by reference to the small characters on the keyboard.

These machines also contain a device comprising a lever or key 58 which is operable effectively to interrupt operation of the printing hammers 27 and thereby prevent record of any number introduced into the adding wheels as shown in Fig. 2. The example of subtraction is performed without recording the subtrahend complement, and this is effected by use of this well known device found in these machines. For convenience of operation I have located the subtraction key 31 adjacent to the non-printing device 58, so that the operator may manipulate both of said devices by the use of one hand.

These machines also contain mechanism for holding the adding wheels 28 inoperative when any record is being produced, and by embodying my present invention in such machines I am enabled to record the subtrahend number itself without interfering with the proper operation of the machine when the complementary number is introduced. Figs. 3 and 4 show examples in which the minuend and subtrahend both are recorded, the character "E" at the left indicating that the subtrahend has not been added into the adding mechanism.

After the remainder number has been determined as shown at "D" in Figs. 3 and 4, said number may be recorded in the same way that totals are recorded. The mechanism for recording the totals and remainders comprises a totals-recording key 59 arranged in the keyboard and operatively connected through a series of levers 60 with a link 61 which extends to the rear of the machine and is pivoted to an arm 62 on a shaft 63. The arm 62 projects above the shaft 63 and with another arm 64 supports a rod 65. The pivoted plate 30 in the carriage 4 is connected with a sliding plate 66 by a pin on said plate 30 extending into an oblique slot 67 in said sliding plate. The sliding plate is actuated rearwardly by a spring and thereby holds the plate 30 normally in front of the heels 24 on the racks when the carriage is in its idle position. Depression of the totals-recording key will cause the rod 65 to push the plate 66 forward and thereby depress the detaining plate 30 below the heels of the racks and permit the latter to be moved forwardly in the usual way to record the total or number represented in the adding wheels and restore said wheels to clear condition.

I am aware that there may be modifications and alterations in the construction

and arrangement of the parts embodying this invention without departure from the spirit and scope of the invention, and I do not restrict myself to identical features of construction or arrangement, but

5 5. What I claim and desire to secure by Letters Patent is—

10 1. In a machine of the class mentioned, adding mechanism operable to carry or transfer from lower to higher orders throughout, and a key for interrupting carrying or transferring at any desired point in said adding mechanism whenever any number is introduced therein, substantially as described.

15 2. In a machine of the character described, devices operable to represent numbers, adding mechanism operable to carry or transfer from lower to higher orders throughout, means for introducing numbers represented by said "devices" into said adding mechanism, and a key adjustable to interrupt carrying beyond the highest order of any number so introduced, substantially as described.

20 3. In an adding machine, a carriage, devices in said carriage adjustable to represent numbers, recording mechanism, means for operating said recording mechanism to record a number represented in said carriage, adding mechanism operated incidentally to the operation of said recording mechanism, and manipulative means whereby the digit added in units order may be increased one unit over the digit recorded, in subtracting operations, substantially as described.

25 4. In an adding machine, adding mechanism, mechanism for causing said adding mechanism to add numbers and to transfer or carry from lower to higher orders, a key, and means controlled by said key effectively to interrupt transferring or carrying at any order in said adding mechanism, the order at which the interruption is effected being automatically determined.

30 5. In an adding machine, the combination with adding mechanism operable to add numbers and to transfer from lower to higher orders, of a subtraction key, and devices adjustable thereby whereby carrying in said adding mechanism may be interrupted or prevented beyond the highest order of any number in said adding mechanism.

35 6. In a machine of the character described, a movable carriage, devices operable to set up numbers in said carriage, adding mechanism, means for operating said adding mechanism to add the numbers set up in said carriage, and means for preventing carrying or transferring in said adding mechanism in certain instances, substantially as described.

40 7. In a machine of the character de-

scribed, a carriage, means to set up numbers in said carriage, adding mechanism, means for operating said adding mechanism to add numbers set up in the carriage, and devices adjustable in subtracting operations to prevent carrying from lower to higher orders in said adding mechanism.

45 8. In a machine of the character described, a movable carriage, devices adjustable in said carriage to represent numbers, adding mechanism, racks operable effectively to introduce into said adding mechanism the numbers set up in the carriage and to carry or transfer from lower to higher orders in adding, and means for preventing said racks from operating to carry, substantially as described.

50 9. In an adding machine, the combination with recording mechanism, and automatic devices operable to add numbers recorded, of a key to prevent carrying in said automatic devices beyond the order of any number recorded having as many orders as are contained in any number represented in said automatic devices, substantially as described.

55 10. The combination with mechanism operable to record numbers, adding mechanism operable to add the numbers recorded and to transfer from lower to higher orders in performing functions of addition, of devices adjustable to prevent carrying beyond the highest order of the number being added while permitting transferring up to the highest order of said number and a single key controlling said devices.

60 11. In an adding machine, the combination with adding and recording devices, of a series of stops, and a key for adjusting said stops to prevent carrying from lower to higher orders by said adding devices, substantially as described.

65 12. In an adding machine, the combination with adding mechanism, racks for operating said adding mechanism to introduce numbers therein and to carry from lower to higher orders, of a series of stops, and means for adjusting said stops to prevent said racks from operating to carry, substantially as described.

70 13. In an adding machine, the combination with adding wheels, racks for operating said wheels to add numbers and to carry from lower to higher orders, and mechanism for recording the numbers added, of mechanism adjustable in subtracting operations to prevent carrying beyond the minuend number when said adding mechanism is operated, substantially as described.

75 14. In an adding machine, the combination with adding wheels, racks for operating said wheels to add numbers and to transfer from lower to higher orders, a carriage controlling the operation of said racks in one direction, and mechanism for recording the

numbers added, of mechanism adjustable in subtracting operations to prevent carrying beyond a predetermined point in the adding mechanism.

5 15. In an adding machine, multiple order adding mechanism, means for carrying from lower to higher orders in said adding mechanism, a carriage whose operation is necessary before said adding mechanism may be operated, and means for preventing carrying any orders beyond the position of said carriage.

10 16. In an adding machine, adding mechanism, means for carrying from lower to higher orders in said adding mechanism, a carriage whose operation is necessary before said adding mechanism may be operated, means for moving said carriage, step by step, from lower to higher orders, and means 20 for preventing operation of said carrying means beyond the order to which said carriage has been moved.

15 17. In an adding machine, the combination with adding and recording mechanism, a carriage whose operation is necessary before said mechanism may be operated, and means for operating said carriage, of a series of stops, a key for adjusting said stops to prevent carrying from lower to higher 30 orders by said adding mechanism as determined by the position of said carriage, substantially as specified.

20 18. In an adding machine, the combination with mechanism operable to record numbers, adding mechanism operable to add the numbers recorded and to transfer from lower to higher orders performing functions of addition, a carriage whose operation is necessary before said recording and adding mechanism may be operated and means for operating said carriage, of devices adjustable to prevent carrying beyond the highest order of the number being added while permitting carrying up to the highest order of 45 said number as determined by the position of said carriage.

25 19. The combination with mechanism operable to record numbers, adding mechanism operable to add the numbers recorded and 50 to transfer from lower to higher orders in performing functions of addition, a carriage whose operation is necessary before said adding and recording mechanism may be operated and means for operating said carriage,

35 55. of devices adjustable to prevent carrying beyond the highest order of the number being added while permitting carrying up to the highest order of said number as determined by the position of said carriage, 60 and a key for operating said devices, substantially as specified.

20. In an adding machine, the combina-

tion with adding wheels, racks for operating said wheels to add numbers and to carry from lower to higher orders, mechanism for recording the numbers added, a carriage whose operation is necessary before any number may be added or recorded and means for operating said carriage, of subtracting mechanism adjustable to prevent carrying beyond the minuend number when said adding mechanism is operated in subtracting operations, and means in said carriage controlling said subtracting mechanism to enable said racks to carry to an order determined by the position of said carriage, substantially as specified.

21. In an adding machine, the combination with adding wheels, racks for operating said wheels to add numbers and to carry from lower to higher orders, springs for operating said racks in carrying operations, a carriage whose operation is necessary before said racks may be operated and means for operating said carriage, of subtracting mechanism adjustable to prevent carrying beyond the minuend number when said adding mechanism is operated, and means in said carriage controlling said subtracting mechanism to enable said racks to operate said adding wheels to an order determined by the position of said carriage, substantially as specified.

22. In an adding machine, the combination with adding wheels, racks for operating said wheels to add numbers and to carry from lower to higher orders, springs for operating said racks, a carriage whose operation is necessary before said racks may be operated and means for operating said carriage, of a series of stops, a key, and connections controlled by said key to prevent carrying beyond the highest order of the number being added as determined by the position of said carriage.

23. In an adding machine, the combination with adding wheels, racks for operating said adding wheels in adding and transferring operations, and a stop for each rack, of a carriage for controlling the racks in adding operations, means for adjusting said stops to prevent operation of said racks in transferring operations, and means in said carriage to prevent adjustment of stops in the numerical orders occupied by said carriage.

In testimony whereof, I hereunto affix my signature to this specification this tenth day of June, 1909, in the presence of two witnesses.

BIRNEY DYSART. [L.S.]
